UNITED STATES PATENT OFFICE

164,379

DESK LAMP

Henry Clay Michie, Brooklyn, N. Y.

Application June 22, 1950, Serial No. 10,691

Term of patent 7 years

(Cl. D48—20)

To all whom it may concern:

Be it known that I, Henry Clay Michie, a citizen of the United States and a resident of Brooklyn, in the county of Kings and State of New York, have invented a new, original, and ornamental Design for Desk Lamp, of which the following is a specification, reference is had to the accompanying drawings, forming part thereof, in which:

Fig. 1 is a perspective view of a desk lamp, showing my new design, the lamp being shown rotated about its intermediate swivel to an extended position.

Figure 2 is a perspective view of the lamp rotated about its upper swivel to reflect light upwardly.

Figure 3 is a perspective view of the lamp rotated slightly about its intermediate swivel.

I claim:

The ornamental design for a desk lamp, as shown.

HENRY CLAY MICHIE.
